US0D1014436S

(12) **United States Design Patent** (10) **Patent No.:** **US D1,014,436 S**
(45) **Date of Patent:** **** Feb. 13, 2024**

(54) **PLATE OF BATTERY MODULE**

(71) Applicants: **Yazaki Corporation**, Tokyo (JP);
TOYOTA JIDOSHA KABUSHIKI KAISHA, Toyota (JP); **KABUSHIKI KAISHA TOYOTA JIDOSHOKKI**, Kariya (JP)

(72) Inventors: **Satoshi Morioka**, Okazaki (JP);
Motoyoshi Okumura, Nagoya (JP);
Hiromi Ueda, Kariya (JP); **Naoto Morisaku**, Kariya (JP); **Yutaro Okazaki**, Kakegawa (JP); **Shinichi Yanagihara**, Kakegawa (JP)

(73) Assignees: **YAZAKI CORPORATION**, Tokyo (JP); **TOYOTA JIDOSHA KABUSHIKI KAISHA**, Toyota (JP); **KABUSHIKI KAISHA TOYOTA JIDOSHOKKI**, Kariya (JP)

(**) Term: **15 Years**

(21) Appl. No.: **29/813,608**

(22) Filed: **Oct. 29, 2021**

(30) **Foreign Application Priority Data**

Apr. 30, 2021 (JP) ..... 2021-009310 D

(51) **LOC (14) Cl.** **13-02**

(57) **CLAIM**

The ornamental design for a plate of battery module, as shown and described.

DESCRIPTION

FIG. 1 is a first perspective view of a plate of battery module showing our new design;

FIG. 2 is a second perspective view thereof;

FIG. 3 is a third perspective view thereof;

FIG. 4 is a fourth perspective view thereof;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof;

FIG. 11 is an enlarged cross-sectional view taken along lines 11-11 shown in FIG. 5;

FIG. 12 is a first perspective view in a closed state thereof;

FIG. 13 is a second perspective view in a closed state thereof; and,

FIG. 14 is a top plan view in a closed state thereof.

1 Claim, 13 Drawing Sheets
